UNITED STATES PATENT OFFICE.

FRANZ AREND, JACOB SCHWALB, AND WILHELM SONNEMANN, OF FRANKFORT-ON-THE-MAIN, GERMANY.

METHOD OF FASTENING THE SCRAPER ARMS FOR MECHANICAL ROASTING FURNACES.

Application filed January 11, 1922. Serial No. 528,415.

To all whom it may concern:

Be it known that we, FRANZ AREND, JACOB SCHWALB, and WILHELM SONNEMANN, residing at Frankfort-on-the-Main, 5 Schweizerstr. 62, Helmholtzstrasse, 29, Wielandstr. 24, Germany, have invented certain new and useful Improvements in Methods of Fastening the Scraper Arms for Mechanical Roasting Furnaces, of which the 10 following is a specification.

The object of the present invention is a method of fastening scraper arms for mechanical roasting furnaces.

The problem on which the invention is 15 based is to provide a firm seating for single scraper arms in their shafts, and in the case of air-cooled arms, to provide that the facings of the air inlet and outlet of the scraper arms abut tightly against the facings of the 20 corresponding outlet and inlet of the hollow shaft, whilst avoiding all means such as, for example, screws, loose wedges, braces and the like, which may suffer or fail, during working, through heat, chemical action and 25 the like.

The invention consists essentially in securing the scraper arm in the pocket of the shaft, by causing two slanting or wedge-shaped projections, which are cast on the 30 shaft and scraper arm respectively, to press against each other, and by causing the rear vertical edge of the end of the scraper arm to bear against a thrust block provided in the shaft pocket, the arm being held and 35 locked in its seating during working by the opposing pressure of the material to be roasted.

In order to understand the invention more clearly, reference is made to the accompanying 40 drawings, which show by way of example an embodiment of the fastening device for the arms applied to an air-cooled scraper arm.

Fig. 1 shows, partly in section, part of the 45 scraper shaft with the arms inserted therein.

Fig. 2 is a cross section at the same part of the shaft.

Fig. 3 shows a front elevation of an arm pocket in the shaft.

Fig. 4 is a cross section through the 50 scraper arm close up against the shaft, along the line X—X of Fig. 1.

The cast scraper shaft H, is provided with 55 two scraper arm pockets B opposite each other. These pockets taper towards the in-

terior of the shaft (see Fig. 2). Each pocket is provided in front at its upper side with a cast on, slanting or wedge-shaped projection F, and at the rear end at the upper side with projections J, and blocks K 60 adapted to take up the thrust. Inasmuch as the example shows an air-cooled scraper arm, air inlet openings G branching off from the shaft bore L, are provided at the bottom of each scraper arm pocket and air exit 65 openings G¹ are provided at the top which lead to the hollow spaces M of the shaft.

The scraper arm has the usual shape tapering towards the point. It is hollow and is divided by means of a cast partition 70 O, into an upper and lower air channel; the lower channel is provided with an air inlet opening and the upper one with an air outlet opening, these openings facing the corresponding openings G, G¹ of the shaft 75 pocket.

That end of the scraper arm which is to be inserted into the shaft is of rectangular cross section and is slightly tapered, corresponding to the shaft pocket. The depth to 80 which the end of the arm penetrates into the shaft pocket is determined by the stop E provided on the body of the arm. The extreme inner end of the arm is provided with a nose C, which, in the working position, 85 fits behind the projection J of the shaft pocket, thus preventing the scraper arm from falling out. A slanting or wedge-shaped projection is cast onto the arm at D, and corresponds to the slanting or wedge-shaped projection F of the shaft pocket so that the inclined surfaces of these wedge-shaped projections D and F when slipped upon each other, occupy the same plane, i. e., 90 that they tighten each other up under pressure. Moreover, in the working position the vertical edge N of the end of the scraper arm bears tightly against the block K which takes up the thrust.

The scraper arm is secured in the shaft 100 pocket in the following manner: The scraper arm, for example A², is inserted into the arm pocket in the tilted position shown on the left-hand side of Fig. 1 until the stop E abuts against the shaft, and the nose C 105 comes into position behind the projection J. Thereupon the scraper arm is lowered to its normal position (Fig. 1 right-hand side A¹), thus causing the nose C of the end of the scraper arm to fit behind the 110

projection J of the scraper arm pocket. The arm is then in the position shown in dotted lines in Fig. 2, and is thereupon pressed into its working position by giving it a short twist in the opposite directions to the normal revolution of the shaft, as shown in Fig. 2, in full lines, so that the surfaces of the wedge-shaped projections D of the scraper arm and F of the arm pocket 10 bear against each other. The purpose of these wedge-shaped or slanting surfaces is, firstly, to press the tightening surfaces G and G¹ connecting the air passages firmly together, and secondly, in conjunction with 15 the thrust block K, to ensure the arm being securely held in the arm pocket when the hollow shaft is revolved. When in work, the arm is firmly fixed and secured in the shaft to the counter pressure of the material to be roasted. The nose C and the stop E serve to secure the scraper arm against shifting longitudinally in the arm pocket, especially in the event of the arm working loose and being dislodged from its working 25 position into the position of insertion (Fig. 2, dotted), through an accidental reverse movement of the shaft. In the subsequent forward movement the arm is automatically tightened up again by means of its wedge-shaped or slanting projection.

The securing device may be used not only with air-cooled scraper arms, but also with ordinary scraper arms unprovided with air cooling channels. In this case, of course, the 35 communicating openings and the corresponding tightening surfaces are dispensed with.

What we claim is:

1. In a roasting furnace, the combination 40 of a rotary shaft, a pocket in the shaft, a wedge extending substantially across the entire width of the pocket, a scraper arm seated within the pocket, and a wedge on the scraper arm cooperating with the wedge on 45 the pocket to hold the arm against rotary displacement when in motion and when at rest.

2. In a roasting furnace, the combination 50 of a rotary shaft, a pocket in the shaft, a wedge of slight inclination extending substantially across the top face of the pocket, a scraper arm seated within the pocket, and a wedge projecting upwardly from the top of the arm cooperating with the wedge on

the pocket to hold the arm firmly in position when in motion and when at rest.

3. In a roasting furnace, the combination 55 of a rotary shaft, a pocket in the shaft, a single scraper arm seated within the pocket, wedges on the pocket and arm which under the opposing pressure exerted by the material being roasted cooperate to lock the arm in the pocket and hold it against rotary displacement relative to the shaft when in motion and when at rest, and means on the 60 arm cooperating with the pocket holding the arm against longitudinal displacement.

4. In a roasting furnace, the combination 65 of a rotary shaft, a pocket in the shaft, an air-cooled scraper arm seated within the 70 pocket, an air passage in the arm having inlet and outlet openings situated near the inner end of the arm, an air passage in the shaft having openings into the pocket corresponding to the air openings in the arm, 75 wedges on the pocket and arm which under the opposing pressure exerted by the material being roasted cooperate to lock the arm in the pocket and hold it against rotary displacement and hold the corresponding air 80 openings in arm and pocket in operative engagement.

5. In a roasting furnace, the combination 85 of a rotary shaft, a pocket in the shaft, an air-cooled scraper arm seated within the 90 pocket, an air passage in the arm having inlet and outlet openings situated near the inner end of the arm, one on the upper and one on the lower face thereof, an air passage in the shaft having openings into the pocket 95 corresponding to the air openings in the arm, a wedge of slight inclination extending substantially across the top of the pocket, and a wedge projecting upwardly from the top face of the arm cooperating with the 100 wedge on the pocket to hold the arm against rotary displacement, and hold the corresponding air openings in arm and pocket in operative engagement.

In testimony whereof we affix our signatures in presence of two witnesses.

FRANZ AREND.
JACOB SCHWALD.
WILHELM SONNEMANN.
